ICE CREAM CAN HOLDER, LIFTER, AND SCRAPER

Herschel L. Milligan, Nashville, Tenn., assignor of
one-half to James B. Cook, Nashville, Tenn.

Application September 24, 1937, Serial No. 165,602

1 Claim. (Cl. 220—90)

This invention relates to a device for holding an ice cream can and facilitates lifting the can, and for scraping surplus ice cream from the dipper, the general object of the invention being to provide a base, uprights and means for engaging the upper part of the can and a wire stretched across the upper portion of the device for acting as a scraper.

Another object of the invention is to provide a clip for gripping an upper portion of the can to prevent it from turning while filling a dipper therefrom and also to make the device adjustable as to length.

This invention also consists in certain other features of construction and in the combination and arrangement of several parts, to be herein-after fully described, illustrated in the accompanying drawing and specifically pointed out in the appended claim.

20 The drawing shows a perspective view of the device.

In this drawing the numeral 1 indicates the base of the device and is preferably formed of a flat ring of metal with turned up and inwardly curved ears 2 on its periphery for engaging the bead at the bottom of a can. A pair of flat bars 3 have their lower ends bent under the base and riveted or otherwise fastened thereto and each bar has a longitudinally extending slot 4 therein. 25 A flat bar 5 engages the inner face of each of the bars 3 and each pair of the bars 3 and 5 are slidably connected together by the channel iron clip 6 which is fastened to the bar 5 by a bolt 7 which passes through the slot 4. A substantially semi-circular collar 8 has its ends connected to the upper ends of the bars 5 with the collar projecting above the upper ends of said bars.

A spring clip 9 of inverted U-shape has one limb connected to the collar and this clip is 40 adapted to engage a portion of the upper edge of an ice cream can A, shown in dotted lines. An inwardly extending lug 10 is formed on the top of the collar at each end thereof, and each lug has a threaded hole therein for receiving a 45 screw 11 and each lug is provided with the groove 12 for receiving an end part of the wire 13, the ends of said wire being held in place by the screws 11. This wire is held taut and extends

across the collar and acts as a scraper for removing surplus cream from a dipper after the dipper has been filled from the contents of the can.

From the foregoing it will be seen that the device can be adjusted as to its length so that it can be used for cans of different heights and that when a can is seated on the base with a portion of its upper edge engaged by the clip 9 the can can be readily lifted from an ice cream cabinet or the like and placed in the cabinet and the device will prevent the can from turning when the dipper is being used to remove some of the contents thereof and the wire can be used for removing surplus cream from the dipper. By loosening the screws 15 or bolts 7 the collar can be raised or lowered to suit the particular can which is to be used with the device and then the screws are tightened to hold the parts in adjusted position. The upwardly and inwardly curved lugs 2 on the base 20 will act to lock the bottom part of a can to the base when the can is provided with a bottom bead and the inwardly extending lugs 10 engage parts of the upper end of the can or container so that these lugs help to hold the can in the device. 25

It is thought from the foregoing description that the advantages and novel features of the invention will be readily apparent.

It is to be understood that changes may be made in the construction and in the combination and arrangement of the several parts, provided, that such changes fall within the scope of the appended claim.

Having described the invention, what is claimed as new is:

A container holder comprising a flat base part, forming a seat for a container, a pair of uprights connected at their lower ends to edge portions of the base part, a substantially semi-circular collar connected to the upper ends of said uprights, inwardly extending lugs connected with the top of the collar at the ends thereof and adapted to engage top portions of a container, each last-mentioned lug having a slit therein, a wire having its ends passing through the slits, and means 40 for holding the ends of the wire in said slits with the wire extending taut between the lugs. 45
